(57) **CLAIM**

The ornamental design for a drawer, as shown and described.

DESCRIPTION

The present application is related to pending U.S. Utility patent application Ser. No. 11/851,165, entitled “Storage and Organization System and Components Thereof,” filed Sep. 6, 2007; pending U.S. Design application Ser. No. 29/284,375, entitled “Storage Bin,” filed Sep. 6, 2007; pending U.S. Design application Ser. No. 29/284,379, entitled “Lid Portion,” filed Sep. 6, 2007; pending U.S. Design application Ser. No. 29/329,629, entitled “Storage Bin,” filed Dec. 18, 2008; pending U.S. Provisional application Ser. No. 61/160,977, entitled “Storage and Organization System and Connectivity of the Components Therein,” filed Mar. 17, 2009; pending U.S. Provisional application Ser. No. 61/161,019, entitled “Storage and Organization System With Stackable Shells,” filed Mar. 17, 2009; pending U.S. Design application Ser. No. 29/333,915, entitled “Storage Unit and Storage Unit Portions,” filed Mar. 17, 2009; pending U.S. Design application Ser. No. 29/333,917, entitled “Supporting Base,” filed Mar. 17, 2009; and pending U.S. Design application Ser. No. 29/333,918, entitled “Tray,” filed Mar. 17, 2009; all of which are incorporated herein by reference.

FIG. 1 is a top perspective view of a drawer, according to the invention;

FIG. 2 is a bottom perspective view thereof;

FIG. 3 is a top view thereof;

FIG. 4 is a bottom view thereof;

FIG. 5 is a front view thereof;

FIG. 6 is a rear view thereof; and,

FIG. 7 is a left side view thereof; the right side view being a mirror image of the right side view.

The broken lines shown in the figures are for illustrative purposes only and form no part of the claimed design.
